UNITED STATES PATENT OFFICE

LAZURE L. GOODMAN, OF INDIANAPOLIS, INDIANA

HOSIERY

Application filed July 29, 1931. Serial No. 553,841.

This invention relates to flat-knit full-fashioned stockings having a welt comprising two thicknesses of fabric. Essentially, it concerns a welt construction in which both the inner and outer fabric extend continuously circumferentially of the stocking so that any strain put on the welt will be equally distributed between the two thicknesses of fabric. In accomplishing this result, I propose to provide a seam construction for the welt different from that now generally utilized and to produce the desired seaming according to novel practices.

It is now the general practice in assembling flat knit stocking blanks having a double welt to seam up the outer welt fabric in line with the seam of the leg fabric, but to leave the edges of the inner fabric free except at the ends which meet the fabric of the leg portion and the outer welt fabric along the welt line. Such construction has the disadvantage of producing an unequal distribution of strain such that the outer welt fabric is more susceptible to runs. Furthermore, the stocking supporting instrumentalities now commonly in use often require a connection along the rear seam of the stocking so that, due to the hole formed along the edge of the inner fabric of the welt, only a single thickness of fabric is available with which to associate the supporting means, thus increasing the danger of runs or holes.

By the herein contemplated construction, the welt is completely seamed along the edges of both the inner and outer fabric with the result that a double thickness of material is provided at all points circumferentially of the stocking, thus permitting supporting means to be connected in proper position to a double thickness of fabric. A particular advantage resides in the fact that a supporter can be connected at the very rear of a stocking to maintain the seam straight and in alignment with the leg. Further, by reason of the distribution of the strain, runs are less likely to occur due to overstretching of the welt, and the two thicknesses of the welts being under equal tension will present a neater appearance.

In accomplishing the above stated general

objects, the edges of both the inner and outer fabric of the welt may be joined in a single seam in continuation of that of the leg portion of the stocking. However, such a construction produces a bulky seam with accompanying discomfort to the wearer and detracts from the flexible and form fitting character of the welt. Hence, in the preferred embodiment of my invention I propose to provide separate seams to unite the edges of the inner and outer fabric of the double welt, so that the inner and outer plies of the welt are free from each other at the seam.

In seaming up a stocking in accordance with my preferred embodiment, the edges of one thickness of the fabric may be seamed from the welt line to the welt top and the seam for the other thickness of fabric may be formed as a continuation of the seam of the leg portion of the stocking. While, of course, the seaming may be effected relative to either side of the fabric in the inner or outer portions of the welt, it is preferable that for the sake of appearance, the seaming should lie inwardly of the exposed surface of the stocking. Preferably, also, the seams for the respective inner and outer welt fabrics should extend on corresponding sides rather than facing each other with a view of preventing the two seams from interfering with each other in such a way as might cause discomfort to the wearer and detract from the elasticity of the welt.

In the accompanying drawing, I have illustrated the preferred embodiment of my invention, wherein:

Fig. 1 is a fragmentary view of the stocking taken from the front with a portion broken away to illustrate the seam construction for the inner welt fabric according to my present invention;

Fig. 2 is a fragmentary view corresponding to Fig. 1 showing the appearance of the outer welt seam which, in effect, is similar to known practices;

Fig. 3 is a sectional view taken on the line 3-3 of Fig. 1 illustrating clearly the seam construction for the double welt according to my invention;

The essential departure of the present in-

vention over known practices resides in the formation of a continuous extending fabric in a welt comprising a double thickness of material. Referring particularly to Fig. 3 and considering in connection therewith Figs.

1 and 2, the numeral 10 indicates the leg portion of a stocking which is adjoined by a welt comprising a double thickness of material in which 11a indicates the outer welt

10 fabric and 11b the inner welt fabric.

The edges of the outer welt fabric 11a are gathered in a seam extending from the welt line 12 to about the top of the stocking and, if desirable, it may be continued slightly be-

15 yond the top downwardly for a short distance to, say, a point x for the express purpose of preventing the end of the seam coming exactly at the top of the stocking. The seam for such portion of the welt is indicated by

20 the numeral 13a. Such construction is essentially similar to known practices.

In order that the inner fabric of the welt may serve to bear a corresponding amount of strain and also to provide a continuously ex-

25 tending double fabric circumferentially of the welt the inner fabric 11b is also seamed from the welt line to the top, the edges thereof being gathered in a seam 13b.

30 Inasmuch as the seam 13a of the outer welt fabric 11a forms a continuation of the leg seam and faces inwardly of the stocking, the seam 13b of the inner welt fabric 11b must terminate slightly short of the line of joinder of the welt and leg fabric as indicated at 14. 35 Preferably the edges of the inner fabric should be free for about an eighth or quarter of an inch to prevent any strain at the point of intersection of the line with the seam inasmuch as such point is an inherently weak

40 portion of a stocking.

It will be noted from Fig. 3 that in the preferred embodiment of the invention the seam 13a in the outer fabric lies on the inward side of the fabric. For the sake of neat appearance and comfort, and to prevent interference between the seams 13a and 13b, it is desirable that the latter be positioned on the inward side so that the respective seams will occupy corresponding positions. With this arrangement, the seaming of the stocking blank may be effected so that the seam for either the outer or inner welt fabric may be made as a continuation of the seam of the leg fabric 10. The seaming of the other portion of the welt fabric will be formed in a separate operation.

I claim:

1. A flat-knit full-fashioned stocking having a double welt, the respective edges of the 60 inner and outer fabric of the welt being seamed together independently one of the other.

2. A flat-knit full-fashioned stocking having a double welt comprising inner and outer 65 portions, and independent seams joining the

edges of the inner and outer portions over substantially their full length, said seams being located on the corresponding sides of the respective inner and outer portions of the welt.

3. A knitted stocking seamed tubular and having a turned or folded welt, said welt being seamed along the edges of both its inner and outer fold independently of each other.

4. A knitted stocking seamed tubular and having a two-ply welt, said plies being seamed along their respective edges free from each other.

5. A knitted stocking seamed tubular and having a two-ply welt, said welt being seamed along the edges of both plies, said two plies being seamed independently.

6. A knitted stocking seamed tubular and having a two-ply welt, the seam of the single ply fabric extending throughout the outer ply and part way along the inner ply, another seam extending substantially from the single ply fabric along the inner ply to meet the other seam.

7. A knitted stocking seamed tubular and having a plural ply welt, and a single ply leg, the seam of the single ply fabric extending throughout the outer ply and part way along the inner ply of the welt, another seam extending substantially from the single ply fabric along the inner ply to meet the other seam, said two seams being free from each other where the single ply fabric and the two plies of the welt meet.

In testimony whereof, I affix my signature.
